UNITED STATES PATENT OFFICE

2,471,342

BRACKET

Arthur E. Nelson, University City, Mo.

Application June 25, 1945, Serial No. 601,485

7 Claims. (Cl. 248—289)

1

The present invention relates to a bracket. More particularly, it relates to a bracket adapted to pivotally support some utensil, such as a kitchen tool, to be held upon a wall surface. Typical of such tools is a can opener.

It is an object of the invention to provide a bracket of this kind that is rigid in construction, durable, and yet of pleasing appearance.

Specifically, it is an object of this invention to provide a bracket having a vertically disposed pivot pin that is secured and reinforced in position.

A further particular object of the invention is to provide such a bracket designed to receive a cover member enshrouding the mechanical parts of the bracket and lending a pleasing appearance thereto.

In the drawings:

Fig. 1 is a plan view of the bracket with the cover removed;

Fig. 2 is a front elevation with the cover removed;

Fig. 3 is a rear elevation with the cover removed;

Fig. 4 is a plan view of the bracket with the cover in place;

Fig. 5 is a front view of the cover alone;

Fig. 6 is a rear elevation of the cover;

Fig. 7 is a front elevation of the entire bracket with the cover in place;

Fig. 8 is a horizontal section taken on the line 8—8 of Fig. 7;

Fig. 9 is a vertical section on the line 9—9 of Fig. 7; and

Fig. 10 is a vertical section on the line 10—10 of Fig. 8.

This bracket comprises a first L-shaped frame member 15, having a vertical portion 16, and a horizontal portion forming a lower shelf 17. A second L-shaped bracket element, generally indicated at 18, has a vertical part 19 secured to the vertical part 16 of the member 15, and projecting laterally slightly beyond the edges of the member 15, as shown. The second bracket element also has a horizontal part forming an upper shelf 20 above and parallel to the shelf 17 of the first bracket. If desired, aligning pins 21 on the second bracket element 18 may engage in a slot 22 on the vertical part 16 of the first bracket element 15. The two vertical portions 16 and 19 are preferably attached together as by spot-welding or the like.

A pivot pin 25 is supported by both of the two horizontal parts 17 and 20. To this end, the pin has a lower reduced portion 26 passing

2

through an opening in the lower horizontal shelf 17. This reduced portion is peened over below the shelf 17 to secure a permanent attachment. Above the shelf 17 and between it and the shelf part 20, the pin is enlarged at 27. Above the enlargement 27, there is a reduced portion 28 that passes through an opening within the upper shelf part 20. The fit of the reduced portion 28 through this opening is tight and may be made by a pressing operation.

It will be seen that the pin is rigidly supported by the two shelves so that it is very strongly held.

The lower shelf 17 has a more or less semi-circular front edge 30, described about the axis of the pin 25 as a center. In the edge 30 are a plurality of notches 31 for a purpose to be described. It will be seen that this semi-circular edge projects beyond the outer limits of the upper shelf 20.

20. An outer cover member, appearing in Figs. 4—6, is adapted to be disposed around the foregoing bracket elements save for the portion of the pin that projects above the upper shelf 20. This cover is generally L-shaped, having a vertical portion 35 with sides 36 providing an indentation from the rear, with overhanging flanges. The bracket members are inserted into this indentation, the vertical portion 16 of the main bracket element 15 fitting between the two overhanging flanges, with the vertical portion 19 of the second bracket element sliding behind the said edges. By this means, the cover is held onto the bracket.

The cover 34 has also a horizontal portion that projects outwardly over the upper shelf 20 at 38, and which is provided with an opening 39 to receive the pin 25. The side portions 40 of the horizontal portion 38 of the cover are downturned, as shown in Fig. 5, to extend downwardly and over the lower shelf 17. These portions 40 have a plurality of notches 43 therein that are adapted to register with the notches 31 in the lower shelf 17 and give access to the latter.

This pin is adapted to support the frame of some device, such as a kitchen tool of which a can opener is an illustration. Such a frame is shown at 48. It has annular ears 50 that are adapted to be installed over the pin 25 to hold the frame 48 for pivotal support on the pin.

50. On its bottom edge, the frame 48 has a depending lug 51. It will be seen that the lower of the two ears 50 slips down until it rests upon the top surface of the horizontal part 38 of the cover member. The depending lug 51 projects downwardly a sufficient distance to fit within the

notches 43 in the side portions 40 of the cover member, and into the notches 31 in the lower shelf 17 of the bracket. As the notches 43 and 31 are radially disposed about the pivot pin 25 as a center, it will be seen that by elevating the frame 48 a sufficient distance, so that the lug 51 clears the notches 43, the frame may be turned to any suitable angular position and then lowered so that it will be held securely in that position.

This bracket is very substantial because the pivot pin 25 is supported at two different elevations. Yet it requires a minimum number of parts, there being only four parts in all. It can be made from stampings for the two bracket portions and a plastic molding for the cover member. While the bracket can be used without the cover member, the latter forms a concealing means for the mechanical parts that results in a bracket with a very pleasing appearance. The cover may be removed, if it is desired to clean out the bracket part, by sliding it upwardly.

The bracket portion is held to a wall or the like by screws that pass through openings in the metal parts. Preferably the screws pass through both vertical bracket portions 16 and 19 to give added assurance of their holding together. Thereafter, the cover part is slipped down over the bracket member, where it remains securely in place.

What is claimed is:

1. In a bracket device, a plurality of L-shaped bracket elements the backs of which are secured together to provide two spaced shelves projecting therefrom, a pin secured in both of said shelves and projecting upwardly therefrom, and a cover member removably secured over said bracket elements, said cover member having a hole through which the pin projects.

2. In a bracket device, a plurality of L-shaped bracket elements the backs of which are secured together to provide two spaced shelves projecting therefrom, and a pin secured in both of said shelves and projecting upwardly therefrom, said pin being united to one shelf, and passing through an opening in the second shelf, with a press-fit.

3. In a bracket device, a plurality of L-shaped bracket elements the backs of which are secured together to provide two spaced shelves projecting therefrom, and a pin secured in both of said shelves and projecting upwardly therefrom, said shelves having aligned openings therein, the pin having an enlarged portion adapted to be disposed between the shelves, with a reduced portion at each end of the enlarged portion, to fit through said openings, one of said reduced portions being fixedly secured through its opening and the other reduced portion fitting through its opening with a binding fit.

4. In a bracket device, a first L-shaped bracket member having a first back wall and a first projecting shelf, a pivot pin secured to said shelf, a second L-shaped bracket member having a second back wall and a second projecting shelf, said sec-

ond back wall and first back wall being attached together with the two shelves in spaced relationship one over the other, said second shelf having a hole to receive and engage the pin, the second back wall, superposed in front of the first one, projecting laterally beyond the first, a generally L-shaped cover member having a back wall with edges engageable around the overhanging second back wall, and a projecting portion to cover both the first and second shelves, said projecting portion and one of said shelves having notches concentric with the pivot pin.

5. In a bracket device, a first L-shaped bracket member, a second L-shaped bracket member, said members being secured together with the backs in contiguous relation and the shelf portions in parallel spaced relation, aligned apertures in said shelf portions, a mounting pin secured in said apertures and extending upwardly therefrom to receive a mount above said shelf portions, said upper shelf portion being of less area than said lower shelf portion, and radial slots in the edge of said lower shelf adapted to receive a mount edge.

6. In a bracket device, two L-shaped bracket elements, said elements being secured together with the backs thereof in contiguous relation and the shelves in spaced relation, and a pin secured in both of said shelves and extending upwardly including a portion above the shelves adapted to receive a mount.

7. In a bracket device, a first L-shaped bracket member having a first back wall and a first projecting shelf, a pivot pin secured to said shelf, a second L-shaped bracket member having a second back wall and a second projecting shelf, said back wall and first back wall being attached together with the two shelves in spaced relationship, one over the other, said second shelf having a hole to receive and engage the pin, the second back wall, superposed in front of the first one, projecting laterally beyond the first, a generally L-shaped cover member having a back wall with edges engageable around the overhanging second back wall, and a projecting portion to cover both the first and second shelves.
